(57) **CLAIM**

(21) Appl. No.: **29/229,447**

The ornamental design for a combined film and digital disk storage container, as shown and described.

(22) Filed: **May 9, 2005**

DESCRIPTION

(51) **LOC (8) Cl. 06-02**

FIG. 1 is a perspective view of a combined film and digital disk storage container showing my new design;

(52) **U.S. Cl. D6/635; D6/632**

FIG. 2 is a top plan view thereof;

(58) **Field of Classification Search D6/407,**

FIG. 3 is a front elevation view thereof;

D6/450, 626–635; D9/433, 422, 418, 428,

FIG. 4 is a rear elevation view thereof;

D9/522, 523, 544, 663; D3/303, 294, 218;

FIG. 5 is a bottom plan view thereof;

D14/479, 478, 474; 206/751, 755, 457, 312,

FIG. 6 is a perspective view thereof, the disk compartment opened;

206/311, 310, 309, 308.2, 308.1, 307, 303,

FIG. 7 is a perspective view of a second embodiment of the design of FIG. 1;

206/232, 579, 493, 472; 720/719, 655, 728,

FIG. 8 is a top plan view thereof; and,

720/734; 211/40; 53/445, 462

FIG. 9 is an exploded perspective view thereof, the disk compartment opened.

See application file for complete search history.
